(57) **CLAIM**

The ornamental design for a baseball diamond-shaped ladderball game, as shown and described.

DESCRIPTION

FIG. 1 is a top right perspective view of a baseball diamond-shaped ladderball game showing my new design;

FIG. 2, is a front elevational view thereof;

FIG. 3 is a rear elevational view thereof;

FIG. 4 is a left-side, elevational view thereof;

FIG. 5 is a right-side, elevational view thereof;

FIG. 6 is a top, plan-view thereof; and,

FIG. 7 is a bottom, plan view thereof.

The broken lines shown in the drawings depict portions of the baseball diamond-shaped ladderball game that form no part of the claimed design.

1 Claim, 7 Drawing Sheets
